(57) **ABSTRACT**

A casting mold includes a cover member covering the inner wall of a bent portion (a first bent portion, etc.) of a passageway. The cover member has a bottomed cylindrical shape having an axis extending in an up-down direction, and includes an upper hole, lateral holes, and at least one flange (a side wall flange). At least one of a fixed mold and a movable mold includes a flange housing groove in a separation surface. When the cover member is disposed in the bent portion and the casting mold is closed, the flange is housed in the flange housing groove, and the cover member is held in a state where a gap is formed between the inner wall of the bent portion and the outer wall of the cover member.

CASTING MOLD

**CROSS-REFERENCE TO RELATED
APPLICATION**

This application is based upon and claims the benefit of priority from Japanese Patent Application No. 2020-140949 filed on Aug. 24, 2020, the contents of which are incorporated herein by reference.

BACKGROUND OF THE INVENTION

Field of the Invention

The present invention relates to a casting mold used in casting.

Description of the Related Art

Various metal products are used for power trains or the like of a vehicle. For example, metal products are formed by casting. JP 6029444 B2 discloses a casting mold used in a gravity casting method or a low pressure casting method. This casting mold includes a branch portion forming body made of a tungsten alloy on the upstream side of a branch point. This structure improves the heat resistance of the portion upstream of the branch point.

SUMMARY OF THE INVENTION

The branch portion forming body disclosed in JP 6029444 B2 includes a first divided piece attached to a fixed mold and a second divided piece attached to a movable mold. The branch portion forming body is formed by combining the first divided piece and the second divided piece as the mold closes. When molten metal flows through the branch portion forming body, the first divided piece and the second divided piece thermally expand individually. At this time, a gap is generated on the mating surface (separation surface) of the casting mold, and the molten metal may leak from the gap. Then, penetration (a phenomenon in which molten metal enters) occurs on the mating surface, and solidified metal adheres to the mating surface. In this case, maintenance work for removing the adhered metal is required. As the number of maintenance operations increases, the operation rate of the casting mold decreases and the production amount of metal parts decreases.

An object of the present invention is to solve the above-described problems.

An aspect of the present invention is a casting mold comprising a fixed mold and a movable mold, and including a cavity formed in a separation surface and configured to mold a product, and a pouring basin and a passageway that are formed in the separation surface and configured to guide molten metal into the cavity, the casting mold further comprising a cover member configured to cover an inner wall of a bent portion that is provided in the passageway and is configured to change an advancing direction of the molten metal, the cover member being configured to allow the passageway positioned on an upstream side of the bent portion to communicate with the passageway positioned on a downstream side of the bent portion, and having a lower thermal conductivity than a base material of the casting mold, wherein the cover member has a bottomed cylindrical shape having an axis extending in an up-down direction, and includes: an upper hole provided at an upper end thereof and opening upward; a lateral hole provided on a side wall

2

thereof and opening in a lateral direction; and at least one flange provided on the side wall thereof and extending in the up-down direction, at least one of the fixed mold and the movable mold includes a flange housing groove in the separation surface, and when the cover member is disposed in the bent portion and the casting mold is closed, the flange is housed in the flange housing groove, and the cover member is held in a state where a gap is formed between the inner wall of the bent portion and an outer wall of the cover member.

According to the present invention, it is possible to reduce the number of maintenance operations due to adhesion of metal.

The above and other objects features and advantages of the present invention will become more apparent from the following description when taken in conjunction with the accompanying drawings in which a preferred embodiment of the present invention is shown by way of illustrative example.

BRIEF DESCRIPTION OF THE DRAWINGS

FIG. 1 is a view showing an overall configuration of an insert mounting device;

FIG. 2 is a view showing a fixed mold (movable mold) viewed from a separation surface side;

FIGS. 3A, 3B and 3C are views respectively showing a front surface, a left side surface, and a plane of a cover member;

FIG. 4 is a view showing a cover housing portion and its peripheral structure viewed from the separation surface side;

FIG. 5 is a cross-sectional view of the periphery of the cover member of a closed mold taken along line V-V (XY plane) in FIG. 4;

FIG. 6 is a graph showing the relationship between the width of a gap and the molten metal leakage length;

FIG. 7 is a view showing a state in which the cover member is displaced in the cross section shown in FIG. 5;

FIG. 8 is a cross-sectional view of the bottom portion of the cover member taken along line VIII-VIII (XY plane) in FIG. 3A;

FIG. 9 is a cross-sectional view of the periphery of the cover member of the closed mold taken along line IX-IX (XY plane) in FIG. 4;

FIG. 10 is a view showing the cover member and a hand;

FIG. 11 is a cross-sectional view of the cover member and the hand taken along line XI-XI in FIG. 10;

FIG. 12 is a cross-sectional view of the cover member and the hand taken along line XII-XII of FIG. 10;

FIG. 13 is a cross-sectional view of the cover member and the hand taken along line XIII-XIII in FIG. 10;

FIG. 14 is a flowchart of a series of operations for mounting the cover member to the cover housing portion.

FIGS. 15A, 15B and 15C are views respectively showing a front surface, a left side surface, and a plane of a cover member having a different form from that of the cover member of FIGS. 3A, 3B and 3C;

FIG. 16 is a cross-sectional view of another embodiment different from the embodiment shown in FIG. 5; and

FIG. 17 is a cross-sectional view of another embodiment different from the embodiment shown in FIG. 5.

**DESCRIPTION OF THE PREFERRED
EMBODIMENTS**

In the following description, directions such as an X direction, a Y direction, and a Z direction are used. The X

direction and the Y direction are orthogonal to each other. The X direction and the Y direction are parallel to the horizontal direction. The Z direction is orthogonal to the X direction and the Y direction. The Z direction is parallel to the up-down direction (vertical direction). The forward direction of each direction is defined as +, and the reverse direction thereof is defined as -.

1. Insert Mounting Device 10

An insert mounting device 10 will be described with reference to FIG. 1. The insert mounting device 10 mounts an insert in a casting mold 40 by using a robot 12. In the present embodiment, the insert mounted in the casting mold 40 is a cover member 72.

The insert mounting device 10 includes the robot 12, a controller 14, and a casting machine 16. In FIG. 1, the robot 12 and the casting machine 16 are shown separated from each other. However, the robot 12 is actually disposed at a position where a hand 24 can reach the casting mold 40.

2. Robot 12

The robot 12 is an industrial robot. The robot 12 includes a robot base 20, an arm 22, and the hand (gripping portion) 24. The arm 22 is attached to the robot base 20. The arm 22 has a plurality of joints and a plurality of links. The hand 24 is attached to the distal end of the arm 22. The hand 24 will be described in [11] below. The operation of the robot 12 is controlled by the controller 14.

3. Controller 14

The controller 14 is a computer including an input device, an arithmetic device, and a storage device (none of which are shown). The input device is a man-machine interface. For example, the arithmetic device is a processor. For example, the storage device is a memory such as a RAM and a ROM. The controller 14 stores the operation of the robot 12 by teaching performed in advance. The operation of the robot 12 includes a mounting operation of mounting the insert (cover member 72) in the casting mold 40. The controller 14 causes the robot 12 to reproduce various operations in accordance with predetermined operations performed by a user using the input device (not shown).

4. Casting Machine 16

The casting machine 16 includes a casting base 26, a fixed platen 28, a movable platen 30, a cylinder support 32, a cylinder 34, and the casting mold 40. The casting mold 40 has a fixed mold 42 and a movable mold 44. On the casting base 26, for example, the fixed platen 28, the movable platen 30, and the cylinder support 32 are arranged in this order from the -X direction toward the +X direction. The fixed platen 28 is fixed to the casting base 26. The movable platen 30 is movable in the -X direction and the +X direction along a guide (not shown) provided in the casting base 26. The casting mold 40 is disposed between the fixed platen 28 and the movable platen 30. The fixed mold 42 is attachable to and detachable from the surface of the fixed platen 28 facing in the +X direction. The movable mold 44 is attachable to and detachable from the surface of the movable platen 30 facing in the -X direction. The cylinder support 32 is fixed to the casting base 26. A cylinder tube 36 of the cylinder 34 is fixed to the surface of the cylinder support 32 facing in the +X direction. The cylinder support 32 has formed therein a

hole (not shown) penetrating therethrough along the X direction. A piston rod 38 is inserted through the hole. An end portion of the piston rod 38 in the -X direction is fixed to the surface of the movable platen 30 facing in the +X direction. An end portion (not shown) of the piston rod 38 in the +X direction is fixed to a piston (not shown). The piston is slidably in the cylinder tube 36 along the X direction.

When fluid is supplied to a first fluid chamber (not shown) 10 of the cylinder tube 36, the piston is pushed in the -X direction. Then, the piston rod 38 and the movable platen 30 move in the -X direction to close the casting mold 40. When fluid is supplied to a second fluid chamber (not shown) of the cylinder tube 36, the piston is pushed in the +X direction. 15 Then, the piston rod 38 and the movable platen 30 move in the +X direction to open the casting mold 40.

5. Casting Mold 40

20 The casting mold 40 will be described with reference to FIG. 2. As described above, the casting mold 40 includes the fixed mold 42 and the movable mold 44. In a state where the casting mold 40 is closed, the fixed mold 42 and the movable mold 44 are symmetrical with respect to a mold mating surface (separation surface 46). Therefore, the fixed mold 42 will be described below, and the description of the movable mold 44 will be omitted. When the following description is read as the description of the movable mold 44, the +Y direction and the -Y direction in FIG. 2 are reversed.

25 The fixed mold 42 includes a first mold 50, a second mold 52, a third mold 54, a fourth mold 56, and a fifth mold 58. Each mold is made of, for example, copper. The first mold 50 is a main body (mold main body) of the fixed mold 42. The first mold 50 has a first separation surface 46a. The first 30 separation surface 46a is a part of the separation surface 46. The first mold 50 further includes an attachment surface (not shown) recessed in the -X direction from the first separation surface 46a. The second mold 52 to the fifth mold 58 are components (partial molds) attached to the attachment surface (not shown) of the first mold 50 by bolts or the like. The second mold 52 has a second separation surface 46b. The third mold 54 has a third separation surface 46c. The fourth mold 56 has a fourth separation surface 46d. The fifth mold 58 has a fifth separation surface 46e. The second separation 35 surface 46b to the fifth separation surface 46e are parts of the separation surface 46. In a state in which the second mold 52 to the fifth mold 58 are attached to the first mold 50, the first separation surface 46a to the fifth separation surface 46e are flush with each other. Thus, the separation surface 46 of the fixed mold 42 is formed by the first separation surface 46a to the fifth separation surface 46e.

40 The first mold 50 has two first separation surfaces 46a. One of the first separation surfaces 46a and the other of the first separation surfaces 46a are separated from each other in the +Y direction. The second mold 52 is positioned at the center of the upper portion of the fixed mold 42. The second separation surface 46b is located between one of the first separation surfaces 46a and the other of the first separation surfaces 46a. The second mold 52 has a lower surface facing in the -Z direction. The third mold 54 abuts against the lower surface of the second mold 52. The third separation surface 46c is located immediately below the second separation surface 46b. The third separation surface 46c is located between one of the first separation surfaces 46a and the other of the first separation surfaces 46a. The fourth mold 56 is positioned in the lower portion of the fixed mold 42. The fourth separation surface 46d is located immediately 45

below one of the first separation surfaces 46a. The fourth separation surface 46d is located immediately below the third separation surface 46c. The fifth mold 58 is positioned in the lower portion of the fixed mold 42. The fifth separation surface 46e is located immediately below the other of the first separation surfaces 46a. The fifth separation surface 46e is located immediately below the third separation surface 46c. The position (height position) of the fourth mold 56 in the Z direction is the same as the position (height position) of the fifth mold 58 in the Z direction. The third mold 54, the fourth mold 56, and the fifth mold 58 form a passageway 62 described later. The third mold 54, the fourth mold 56, and the fifth mold 58 are arranged along the flow direction of the molten metal.

The fixed mold 42 includes a half of a pouring basin 60, a half of the passageway 62 (corresponding to a sprue, a runner, and a gate), and a half of a cavity 64. Each half is recessed in the -X direction from the separation surface 46. When the casting mold 40 is closed, the halves are mated together. As a result, the pouring basin 60, the passageway 62 and the cavity 64 are formed.

The pouring basin 60 is formed in the second mold 52. The pouring basin 60 opens in the +Z direction (upward direction). The pouring basin 60 has a tapered shape whose diameter decreases toward the -Z direction (downward direction).

The cavity 64 is formed in the first mold 50. Six cavities 64 are shown in FIG. 2. For example, a camshaft or balancer shaft of a vehicle is formed using the cavity 64. Three cavities 64 are formed in one of the first separation surfaces 46a. Three cavities 64 are also formed in the other of the first separation surfaces 46a.

The passageway 62 is formed across the third mold 54, the fourth mold 56, and the fifth mold 58. A first bent portion 66 and two second bent portions 68 are formed in the passageway 62. The first bent portion 66 and the two second bent portions 68 are located below the pouring basin 60 and the cavities 64. The passageway 62 extends downward (-Z direction) from the pouring basin 60 and branches in the lateral direction ($\pm Y$ direction) at the first bent portion 66. The passageway 62 extends in the +Y direction from the first bent portion 66 and is bent upward (in the +Z direction) at the second bent portion 68 on the +Y direction side. The passageway 62 extends upward from the second bent portion 68 and branches into three. The three passageways 62 are directly connected to lower end portions of the three cavities 64 formed in one of the first separation surfaces 46a. Further, the passageway 62 extends in the -Y direction from the first bent portion 66 and is bent upward (in the +Z direction) at the second bent portion 68 on the -Y direction side. The passageway 62 extends upward from the second bent portion 68 and branches into three. The three passageways 62 are directly connected to lower end portions of the three cavities 64 formed in the other of the first separation surfaces 46a.

The molten metal supplied from the pouring basin 60 flows downward (-Z direction) in the passageway 62. The advancing direction of the molten metal is changed to the lateral direction ($\pm Y$ direction) at the first bent portion 66. Further, the molten metal flows through the passageway 62 in the lateral direction ($\pm Y$ direction) and passes through filters 70. The advancing direction of the molten metal is changed to the upward direction (+Z direction) at the second bent portions 68. The molten metal flows into each cavity 64 in the upward direction (+Z direction).

The passageway 62 is more likely to deteriorate than portions other than the passageway 62. In the present embodiment, when the passageway 62 deteriorates, the third

mold 54 to the fifth mold 58 are replaced. Meanwhile, the first mold 50 and the second mold 52 are continuously used. Further, the passageway 62 is divided into three parts across the third mold 54 to the fifth mold 58 with the first bent portion 66 as the center. Therefore, the vertical stress and the lateral stress generated in the fixed mold 42 are reduced.

6. Cover Member 72

10 The cover member 72 is mounted inside the first bent portion 66. The cover member 72 is an insert. The cover member 72 covers the inner wall of the first bent portion 66 and the inner wall of the passageway 62 around the first bent portion 66. In addition, the cover member 72 allows the passageway 62 positioned on the upstream side of the first bent portion 66 to communicate with the passageway 62 positioned on the downstream side of the first bent portion 66. The cover member 72 is formed of a material having a lower thermal conductivity than the member of the fixed mold 42 (base material of the mold). For example, when an iron-based component is cast using the casting mold 40, the cover member 72 is made of an iron-based alloy such as a cold-rolled steel plate (SPCC). When both the cover member 72 and the molten metal are iron-based alloys, the cover member 72 may be re-melted and reused together with the casting design parts (the third mold 54, the fourth mold 56, and the fifth mold 58) separated from the product part (the first mold 50) after casting.

15 The cover member 72 will be described with reference to FIGS. 3A to 3C. The cover member 72 is formed of a single steel plate. The steel plate is subjected to shearing, drawing, and bending. The first end of the steel plate and the second end of the steel plate are joined to each other. Thus, the steel plate is formed into a bottomed cylindrical shape having an axis A. As shown in FIG. 3C, the outer peripheral shape of the cover member 72 viewed from the +Z direction is a substantially regular hexagonal shape when side wall flanges 82 described later are ignored.

20 The cover member 72 has a body portion 74 and a bottom portion 76. The body portion 74 has a tubular shape. The axis A of the body portion 74 extends in the up-down direction (Z direction). The bottom portion 76 extends downward from the lower end of the body portion 74. The cross-sectional area of the bottom portion 76 in the XY plane decreases in the downward direction. An upper hole 78 is formed in an upper end of the body portion 74. The upper hole 78 opens upward. Two lateral holes 80 are formed in the side wall of the body portion 74 above the bottom portion 76. The two lateral holes 80 open in the lateral direction (+Y direction and -Y direction). The upper hole 78 is an inlet of a flow path formed in the cover member 72. The two lateral holes 80 are outlets of the flow path formed in the cover member 72. The upper hole 78 is directly connected to the passageway 62 (the passageway 62 of the third mold 54) positioned on the upstream side of the cover member 72. One of the lateral holes 80 is directly connected to the passageway 62 (the passageway 62 of the fourth mold 56) positioned on the downstream side of the cover member 72. The other of the lateral holes 80 is directly connected to the passageway 62 (the passageway 62 of the fifth mold 58) positioned on the downstream side of the cover member 72. The inner diameter of the upper hole 78 (and the inner diameter of the flow path formed in the cover member 72) are equal to or larger than the inner diameter of the passageway 62 (the passageway 62 of the third mold 54) positioned on the upstream side of the cover member 72. Each inner diameter is preferably the same.

The cover member 72 has a flange. Specifically, the body portion 74 of the cover member 72 has the side wall flange 82 on each of the side walls on both sides in the Y direction. Each side wall flange 82 extends in the up-down direction (Z direction) from the upper hole 78 to the lateral hole 80. Each side wall flange 82 projects outwardly from the outer wall of the cover member 72. Each sidewall flange 82 is parallel to the YZ plane. One of the sidewall flanges 82 is shifted 180 degrees about the axis A relative to the other of the sidewall flanges 82. A bottom flange 84 is formed on the outer wall of the bottom portion 76. The bottom flange 84 extends from the two lateral holes 80 to the lower end of the bottom portion 76. The side wall flange 82 projecting in the +Y direction is a bent part formed by bending a substantially central portion of the steel plate. The side wall flange 82 projecting in the -Y direction is an abutment part formed by the first end of the steel plate and the second end of the steel plate abutting against each other. At the abutment part, the first end of the steel plate and the second end of the steel plate are joined to each other. On the other hand, the bottom flange 84 includes a bent part and an abutment part.

7. Cover Housing Portion 90

The cover housing portion 90 will be described with reference to FIGS. 4 and 5. FIG. 4 shows a part of the fixed mold 42 in which the cover member 72 and the filters 70 shown in FIG. 2 are not mounted. In the passageway 62, the cover housing portion 90 is formed from the first bent portion 66 over a predetermined range on the upstream side thereof (in the +Z direction). The cover housing portion 90 houses the cover member 72 (FIG. 2). The cover housing portion 90 is more widely recessed than the passageway 62 adjacent to the cover housing portion 90. The inner diameter of the cover housing portion 90 is larger than the inner diameter of the passageway 62 positioned on the upstream side of the cover housing portion 90.

The cover housing portion 90 is formed across the third mold 54, the fourth mold 56, and the fifth mold 58. Therefore, the cover housing portion 90 includes abutment portions where two molds abut against each other. Specifically, the cover housing portion 90 includes a first abutment portion 92, a second abutment portion 94, and a third abutment portion 96. At the first abutment portion 92, the third mold 54 and the fourth mold 56 abut against each other. At the second abutment portion 94, the third mold 54 and the fifth mold 58 abut against each other. At the third abutment portion 96, the fourth mold 56 and the fifth mold 58 abut against each other.

Flange housing grooves 100 are formed in an edge of the cover housing portion 90 adjacent to the separation surface 46 (the third separation surface 46c, the fourth separation surface 46d, and the fifth separation surface 46e). In the present embodiment, the flange housing groove 100 that houses the side wall flange 82 projecting in the +Y direction is formed across the third mold 54 and the fourth mold 56. The flange housing groove 100 that houses the side wall flange 82 projecting in the -Y direction is formed across the third mold 54 and the fifth mold 58. The flange housing groove 100 that houses the bottom flange 84 is formed across the fourth mold 56 and the fifth mold 58.

As shown in FIG. 5, the inner peripheral shape of the cover housing portion 90 is similar to the outer peripheral shape of the cover member 72. In the case of the present embodiment, the inner peripheral shape of the cover housing portion 90 is a substantially regular hexagonal shape when the flange housing grooves 100 are ignored. The size of the

cover housing portion 90 is larger than the size of the thermally expanded cover member 72. This prevents the thermally expanded cover member 72 from becoming larger than the cover housing portion 90. Further, at low temperature, a gap 98 is formed between the outer wall of the cover member 72 and the inner wall of the cover housing portion 90.

When the casting mold 40 is closed after the cover member 72 is mounted in the cover housing portion 90, the 10 side wall flanges 82 and the bottom flange 84 are housed in the flange housing grooves 100. It is preferable that the side wall flanges 82 abut against a bottom surface 100a of the flange housing groove 100 of the fixed mold 42 and a bottom surface 100a of the flange housing groove 100 of the 15 movable mold 44.

8. Gap 98 Between Cover Member 72 and Cover Housing Portion 90

20 A width d1 of the gap 98 will be described with reference to FIGS. 5 to 7. When the gap 98 is formed, an air layer is formed around the cover member 72. That is, the gap 98 has a heat insulating function. However, if the width d1 of the gap 98 is too large, the molten metal may enter the gap 98. In the worst case, the molten metal enters the abutment portions (the first abutment portion 92, the second abutment portion 94, and the third abutment portion 96). In this case, the following problems occur.

When the molten metal is cooled and solidified, the metal 30 product formed in the cavity 64, the residual metal remaining in the passageway 62, and the cover member 72 are integrated. Therefore, when the metal product is released from the mold, the residual metal and the cover member 72 are taken out from the mold together with the metal product. 35 When the molten metal enters the abutment portions, burrs are generated around the cover member 72. This makes it difficult to release the metal product from the mold. If the metal product is pushed by a pushing pin or the like in order to release the metal product from the mold, the metal 40 product may be damaged or deformed. In order to prevent such a problem, the gap 98 is required to have a function of preventing the entry of the molten metal.

Therefore, the present inventors studied an appropriate width d1 of the gap 98. In the study, the inventors measured 45 the amount of molten metal leaking from the upper end of the cover member 72 to the gap 98. Specifically, the inventors measured the molten metal leakage length extending downward (in the -Z direction) from the upper end of the cover member 72. Further, the inventors set the threshold value of the allowable molten metal leakage length to 60 [mm]. FIG. 6 shows the measurement results. Concerning the width d1 shown in FIG. 6, the third decimal place is rounded off.

As shown in FIG. 6, when the width d1 of the gap 98 at 55 low temperature is 0.54 [mm] or less, the molten metal leakage length becomes smaller than the threshold value. When the width d1 of the gap 98 at low temperature is 0.55 [mm] or more, the molten metal leakage length becomes larger than the threshold value. From this measurement result, it is understood that, when the width d1 of the gap 98 at low temperature is 0.54 [mm] or less, it is acceptable even if the molten metal enters the gap 98. Further, when the width d1 of the gap 98 at low temperature is larger than 0 [mm], an air layer is formed around the cover member 72. 60 Therefore, a heat insulating effect can be expected. However, even if the width d1 is 0 [mm], since the cover member 72 is formed of a material having low thermal conductivity

as described above, heat insulating effect can be expected to a certain degree. From the above study, the inventors have reached the following conclusion. By setting the width $d1$ of the gap **98** at low temperature to 0 [mm] or more and 0.54 [mm] or less, both the heat insulating function and the function of preventing the entry of the molten metal can be achieved. The inventors have confirmed that this numerical range is applicable to a plurality of casting molds **40** having different structures and sizes.

As shown in FIG. 7, there is a possibility that the cover member **72** is displaced in the Y direction in the cover housing portion **90**. In the present embodiment, the outer peripheral shape of the cover member **72** and the inner peripheral shape of the cover housing portion **90** are substantially regular hexagonal shapes. In this case, in order to set the width $d1$ of the gap **98** to 0.54 [mm] or less over the entire range, it is necessary to consider the deviation in the Y direction. As shown in FIG. 7, it is preferable to design the sizes of the cover member **72** and the cover housing portion **90** so that the width $d1$ of the gap **98** which becomes widest in a state where the cover member **72** is maximally displaced in the -Y direction (or the +Y direction) is 0.54 [mm] or less.

9. Flange Gap 102

As shown in FIG. 8, a gap **102** is formed between the first end of the steel plate and the second end of the steel plate at the distal end of the bottom flange **84**. If a width $d2$ of the gap **102** is too large, there is a possibility that the leakage of the molten metal from the bottom flange **84** exceeds an allowable level. Therefore, the gap **102** also has an appropriate width $d2$.

In order to determine an appropriate width $d2$ of the gap **102**, the inventors confirmed the condition of the molten metal leakage for each width $d2$ of the gap **102**. As a result, the inventors reached the following conclusion. When the width $d2$ of the gap **102** at low temperature is 0.3 [mm] or less, the leakage of the molten metal from the bottom flange **84** can be prevented. This conclusion also applies to the sidewall flange **82**.

10. Magnet 104 for Attracting Cover Member 72

As shown in FIG. 9, a heat-resistant magnet **104** is embedded in the cover housing portion **90** of one of the fixed mold **42** and the movable mold **44**. The magnet **104** attracts the cover member **72**. In the present embodiment, the magnet **104** is embedded in each of the fourth mold **56** of the fixed mold **42** and the fifth mold **58** of the fixed mold **42**. The magnet **104** of the fourth mold **56** and the magnet **104** of the fifth mold **58** are provided at symmetrical positions with respect to the XZ plane passing through the axis A. In a case where the fixed mold **42** is not divided into the fourth mold **56** and the fifth mold **58** but is integrally formed, one magnet **104** may be provided.

11. Hand 24 of Robot 12

The hand **24** provided in the robot **12** (FIG. 1) will be described with reference to FIGS. 10 to 13. In the following description, directions such as an L direction, an M direction, and an N direction are used. The L direction and the M direction are orthogonal to each other. The N direction is orthogonal to the L direction and the M direction. The forward direction of each direction is defined as +, and the reverse direction thereof is defined as -.

The hand **24** can grip the cover member **72** at a predetermined position of the equipment. The hand **24** includes a hand body **110**, a pair of movable portions **112**, an upper holding portion **114**, and a lower holding portion **116**.

The hand body **110** is attached to the distal end portion of the arm **22** (FIG. 1). The hand body **110** supports the pair of movable portions **112**, the upper holding portion **114**, and the lower holding portion **116**. The pair of movable portions **112**, the upper holding portion **114**, and the lower holding portion **116** project from the hand body **110** in the +L direction. The upper holding portion **114** is positioned on the downstream side of the pair of movable portions **112** in the +M direction. The lower holding portion **116** is positioned on the downstream side of the pair of movable portions **112** in the -M direction.

As shown in FIG. 11, the first movable portion **112** is arranged on the downstream side of the second movable portion **112** in the +N direction. A holding claw **118** is formed at the tip of each movable portion **112** in the +L direction. The first movable portion **112** and the second movable portion **112** can approach each other. Arrows P shown in FIG. 11 indicate directions in which the first movable portion **112** and the second movable portion **112** approach each other. The first movable portion **112** and the second movable portion **112** can move away from each other. Arrows Q shown in FIG. 11 indicate directions in which the first movable portion **112** and the second movable portion **112** move away from each other. The holding claw **118** of the first movable portion **112** and the holding claw **118** of the second movable portion **112** protrude toward each other. The pair of movable portions **112** can move in the $\pm N$ directions according to the operation of a motor or the like. The pair of movable portions **112** operate in directions (arrows P) approaching each other. Further, the pair of movable portions **112** grip the cover member **72** by inserting the holding claws **118** into the lateral holes **80** of the cover member **72**. Further, the pair of movable portions **112** operate in directions (arrows Q) away from each other. Further, the pair of movable portions **112** release the cover member **72** by pulling out the holding claws **118** from the lateral holes **80** of the cover member **72**.

When the cover member **72** is attached to the cover housing portion **90**, the cover member **72** is moved in the -X direction to approach the cover housing portion **90**. At this time, each of the holding claws **118** inserted into the lateral holes **80** is positioned in front of the passageway **62**. Therefore, even if the cover member **72** is brought close to the cover housing portion **90**, there is a low possibility that each of the holding claws **118** comes into contact with the separation surface **46**. Thus, according to the present embodiment, the cover member **72** can be brought further closer to the inner wall of the cover housing portion **90**. Further, according to the present embodiment, there is a low possibility that the holding claw **118** comes into contact with the separation surface **46** after the cover member **72** is attached to the cover housing portion **90**.

As shown in FIG. 12, an upper abutment portion **120** is formed at the tip of the upper holding portion **114** in the +L direction. The upper abutment portion **120** abuts against the body portion **74** of the cover member **72**. With this structure, when the pair of movable portions **112** grip the cover member **72**, the cover member **72** is prevented from wobbling.

As shown in FIG. 13, a lower abutment portion **122** is formed at the tip of the lower holding portion **116** in the +L direction. In the LN plane, the shape of the lower abutment portion **122** coincides with a part of the outer peripheral

11

shape of the bottom portion 76 of the cover member 72. Similarly to the bottom portion 76 of the cover member 72, the diameter of the lower abutment portion 122 decreases from the upper side (+M direction) toward the lower side (-M direction). The lower abutment portion 122 abuts against the bottom portion 76 of the cover member 72. The lower abutment portion 122 prevents the cover member 72 from wobbling when the pair of movable portions 112 grip the cover member 72. Further, the lower abutment portion 122 prevents the cover member 72 from displacing downward when the pair of movable portions 112 grip the cover member 72.

12. Operation of Mounting Cover Member 72 in Cover Housing Portion 90

A series of operation procedures in which the robot 12 mounts the cover member 72 in the cover housing portion 90 of the fixed mold 42 will be described with reference to FIG. 14. The controller 14 controls the operation of the robot 12 to perform the following series of operations.

In step S1, the robot 12 moves the hand 24 to a predetermined position in which the cover member 72 is supplied, and grips the cover member 72 with the hand 24. At this time, the robot 12 operates the pair of movable portions 112 in the directions as indicated by the arrows P in FIG. 11 to insert the holding claws 118 into the lateral holes 80 of the cover member 72.

In step S2, the robot 12 conveys the cover member 72 to a position facing the fixed mold 42 while gripping the cover member 72 with the hand 24. The separation surface 46 of the fixed mold 42 is parallel to the up-down direction (Z direction). The robot 12 brings the cover member 72 close to the cover housing portion 90. At this time, the robot 12 directs the upper hole 78 of the cover member 72 upward (in the +Z direction). Further, the robot 12 makes the axis A of the cover member 72 parallel to the up-down direction (Z direction).

In step S3, the robot 12 positions the cover member 72 with respect to the cover housing portion 90. At this time, the robot 12 secures a predetermined clearance between the cover member 72 and the cover housing portion 90. The robot 12 may perform positioning based on a detection value of a sensor that detects a distance between the cover member 72 and the cover housing portion 90. Further, the robot 12 may perform positioning using a camera.

In step S4, the robot 12 releases the cover member 72 and causes the cover member 72 to be attracted to the cover housing portion 90 by the magnetic force of the magnets 104. At this time, the robot 12 operates the pair of movable portions 112 in the directions as indicated by the arrows Q in FIG. 11 to pull out the holding claws 118 from the lateral holes 80 of the cover member 72. Since the predetermined clearance is secured between the cover member 72 and the cover housing portion 90, the cover member 72 is attracted to the cover housing portion 90 without falling.

The robot 12 mounts the filters 70 in the fixed mold 42 before or after mounting the cover member 72 in the cover housing portion 90. After the robot 12 mounts the cover member 72 and the filters 70, the casting machine 16 closes the casting mold 40.

13. Other Embodiments

The outer peripheral shape of the cover member 72 may be a polygonal shape other than the substantially regular hexagonal shape. For example, as shown in FIGS. 15A to

12

15C, the outer peripheral shape of the cover member 72 may be circular. In the cover member 72 shown in FIGS. 15A to 15C, the same components as those of the cover member 72 shown in FIGS. 3A to 3C are denoted by the same reference numerals. The cover member 72 having a circular outer peripheral shape has a side wall flange 82 projecting in the -Y direction and corresponding to the abutment part. The bottom portion 76 is formed by drawing.

In the above embodiment, the inner peripheral shape of the cover housing portion 90 is similar to the outer peripheral shape of the cover member 72. Alternatively, the inner peripheral shape of the cover housing portion 90 and the outer peripheral shape of the cover member 72 may not be similar to each other. For example, as shown in FIG. 16, the outer peripheral shape of the cover member 72 may be a substantially regular hexagonal shape, and the inner peripheral shape of the cover housing portion 90 may be a hexagonal shape elongated in the X direction. In the embodiment shown in FIG. 16, a diameter w1 of the cover housing portion 90 is longer than a diameter w2 and a diameter w3 thereof.

Further, the outer peripheral shape of the cover member 72 may be another polygonal shape, and the inner peripheral shape of the cover housing portion 90 may be a polygonal shape elongated in the X direction.

Further, as shown in FIG. 17, the outer peripheral shape of the cover member 72 may be substantially circular, and the inner peripheral shape of the cover housing portion 90 may be an oval (including an ellipse). A minor axis b of the ellipse may be orthogonal to the separation surface 46 (mold mating surface). A major axis a of the ellipse may be parallel to the separation surface 46 (mold mating surface). For example, a gap 130 is formed between the inner wall of the cover housing portion 90 and the outer wall of the cover member 72. The maximum value of a width d1 of the gap 130 is preferably 0 [mm] or more and 0.54 [mm] or less.

In the embodiment described above, the cover member 72 is mounted in the first bent portion 66. Not only the first bent portion 66 but also the second bent portion 68 may be mounted with the cover member 72 having a shape corresponding to the shape of the second bent portion 68.

In the above-described embodiment, the passageway 62 branches in the +Y direction and the -Y direction at the first bent portion 66. Alternatively, the passageway 62 may be bent only in one direction without branching.

In the above embodiment, the side wall flange 82 is formed by joining both ends of the steel plate. Alternatively, the side wall flange 82 may be formed by bringing both ends of the steel plate into close contact with each other. For example, both ends of the steel plate may be sandwiched between the bottom surface 100a of the flange housing groove 100 of the fixed mold 42 and the bottom surface 100a of the flange housing groove 100 of the movable mold 44 to be in close contact with each other.

In the above embodiment, the cover member 72 is formed of one steel plate. Alternatively, the cover member 72 may be formed of two steel plates. For example, a steel plate recessed in the +X direction and a steel plate recessed in the -X direction may be joined together.

14. Technical Idea Obtained from Embodiment

Technical ideas that can be grasped from the above embodiments will be described below.

An aspect of the present invention is the casting mold 40 comprising the fixed mold 42 and the movable mold 44, and including, in the separation surface 46, the cavity 64 for

molding a product, and the pouring basin 60 and the passageway 62 that guide molten metal into the cavity 64, the casting mold further comprising the cover member 72 which covers the inner wall of the bent portion (the first bent portion 66, the second bent portion 68) that is provided in the passageway 62 and changes the advancing direction of the molten metal, allows the passageway 62 positioned on the upstream side of the bent portion to communicate with the passageway 62 positioned on the downstream side of the bent portion, and has a lower thermal conductivity than the base material of the casting mold, wherein the cover member 72 has a bottomed cylindrical shape having an axis A extending in the up-down direction, and includes: the upper hole 78 provided at an upper end thereof and opening upward; the lateral hole 80 provided on a side wall thereof and opening in the lateral direction; and at least one flange (the side wall flange 82) provided on the side wall thereof and extending in the up-down direction, at least one of the fixed mold 42 and the movable mold 44 includes the flange housing groove 100 in the separation surface 46, and when the cover member 72 is disposed in the bent portion and the casting mold is closed, the flange is housed in the flange housing groove 100, and the cover member 72 is held in a state where the gap 98 is formed between the inner wall of the bent portion and the outer wall of the cover member 72.

In the above configuration, the inner wall of the passageway 62 is covered with the bottomed cylindrical cover member 72. Since the bottomed cylindrical cover member 72 is a single component, the leakage of the molten metal is reduced as compared with a pair of divided pieces combined by mold closing. Therefore, the number of maintenance operations due to the adhesion of metal is reduced. Further, the life of the casting mold 40 is extended. Further, according to the above configuration, it is not necessary to provide the cover member 72 over the entire passageway 62. Therefore, the manufacturing cost of the cover member 72 is reduced. In addition, the cover member 72 can be easily mounted. Furthermore, according to the above-described configuration, the flange (the side wall flange 82) is provided on the cover member 72 side, and the flange housing groove 100 is provided on the mold side. Therefore, it is easy to position the cover member 72 with respect to the bent portion.

In the above aspect, the gap 98 having the width d1 of 0 [mm] or more and 0.54 [mm] or less may be formed between the inner wall of the bent portion (the first bent portion 66, the second bent portion 68) and the outer wall of the cover member 72.

According to the above-described configuration, the width d1 of the gap 98 formed between the bent portion (the first bent portion 66, the second bent portion 68) and the cover member 72 is set to a predetermined range (0 [mm] $\leq$ d1 $\leq$ 0.54 [mm]). According to the above configuration, even if the cover member 72 thermally expands, the entry of the molten metal into the gap 98 is suppressed. Therefore, according to the above-described configuration, the number of maintenance operations due to the adhesion of metal is reduced. Further, the life of the casting mold 40 is extended. Further, according to the above configuration, the gap 98 has a heat insulating function. Therefore, the bent portion is more effectively protected.

In the above aspect, the cover member 72 may be formed in the bottomed cylindrical shape by bending a plate-shaped member, the flange (the side wall flange 82) may be formed at a bent part at which the plate-shaped member is bent or at an abutment part at which both ends of the plate-shaped member abut against each other, and in the flange, the gap

102 having the width d2 of 0 [mm] or more and 0.3 [mm] or less may be formed between the both ends of the plate-shaped member.

According to the above configuration, in the flange, the width d2 of the gap 102 between the both ends of the plate-shaped member falls within a predetermined range (0 [mm] $\leq$ d2 $\leq$ 0.3 [mm]). According to the above-described configuration, the width d2 of the gap 102 is in an appropriate range. Therefore, leakage of the molten metal from the flange is prevented. Therefore, according to the above-described configuration, the number of maintenance operations due to the adhesion of metal is reduced. Further, the life of the casting mold 40 is extended.

In the above aspect, the cover member 72 may include the flange (the sidewall flange 82) at each of positions shifted from each other by 180 degrees about the axis A.

According to the above configuration, it is easy to position the cover member 72 with respect to the bent portion (the first bent portion 66, the second bent portion 68).

In the above aspect, the inner peripheral shape of the cross section of the passageway 62 in the horizontal plane (XY plane) and the outer peripheral shape of the cross section of the cover member 72 in the horizontal plane may be similar to each other.

According to the above configuration, when the cover member 72 thermally expands, the gap 98 between the cover member 72 and the bent portion (the first bent portion 66, the second bent portion 68) is maintained. Therefore, the bent portion is more effectively protected.

In the above aspect, the inner peripheral shape of the cross section of the passageway 62 and the outer peripheral shape of the cross section of the cover member 72 may be polygonal or circular.

In the above aspect, the inner peripheral shape of the cross section of the passageway 62 in the horizontal plane (XY plane) may be an ellipse having a minor axis b orthogonal to the separation surface 46, and a major axis a parallel to the separation surface 46, the outer peripheral shape of the cross section of the cover member 72 in the horizontal plane may be circular, and the maximum value of the width d1 of the gap 130 formed between the inner wall of the passageway 62 on the minor axis b side and the outer wall of the cover member 72 may be 0 [mm] or more and 0.54 [mm] or less.

The casting mold according to the present invention is not limited to the above-described embodiments, and various configurations can be adopted without departing from the gist of the present invention.

What is claimed is:

1. A casting mold comprising a fixed mold and a movable mold, and including a cavity formed in a separation surface and configured to mold a product, and a pouring basin and a passageway that are formed in the separation surface and configured to guide molten metal into the cavity,

the casting mold further comprising a cover member configured to cover an inner wall of a bent portion that is provided in the passageway and is configured to change an advancing direction of the molten metal, the cover member being configured to allow the passageway positioned on an upstream side of the bent portion to communicate with the passageway positioned on a downstream side of the bent portion, and having a lower thermal conductivity than a base material of the casting mold, wherein

the cover member has a bottomed cylindrical shape having an axis extending in a vertical direction, and includes: an upper hole provided at an upper end thereof and opening upward; a lateral hole provided on

15

a side wall thereof and opening in a lateral direction; and at least one flange provided on the side wall thereof and extending in the vertical direction, at least one of the fixed mold and the movable mold includes a flange housing groove in the separation surface, and when the cover member is disposed in the bent portion and the casting mold is closed, the flange is housed in the flange housing groove, and the cover member is held in a state where a gap is formed between the inner wall of the bent portion and an outer wall of the cover member. 10

2. The casting mold according to claim 1, wherein the gap having a width of 0 mm or more and 0.54 mm or less is formed between the inner wall of the bent portion and the outer wall of the cover member. 15

3. The casting mold according to claim 1, wherein the cover member is formed in the bottomed cylindrical shape by bending a plate-shaped member, the flange is formed at a bent part at which the plate-shaped member is bent or at an abutment part at which both ends of the plate-shaped member abut against each other, and in the flange, a gap having a width of 0 mm or more and 0.3 mm or less is formed between the both ends of the plate-shaped member. 20

16

4. The casting mold according to claim 1, wherein the cover member includes the flange at each of positions shifted from each other by 180 degrees about the axis.
5. The casting mold according to claim 1, wherein an inner peripheral shape of a cross section of the passageway in a horizontal plane and an outer peripheral shape of a cross section of the cover member in the horizontal plane are similar to each other.
6. The casting mold according to claim 5, wherein the inner peripheral shape of the cross-section of the passageway and the outer peripheral shape of the cross-section of the cover member are polygonal or circular.
7. The casting mold according to claim 1, wherein an inner peripheral shape of a cross-section of the passageway in a horizontal plane is an ellipse having a minor axis orthogonal to the separation surface, and a major axis parallel to the separation surface, an outer peripheral shape of a cross section of the cover member in the horizontal plane is circular, and a width of the gap formed between the inner wall of the passageway on a side of the minor axis and the outer wall of the cover member is 0 mm or more and 0.54 mm or less.
